UNITED STATES PATENT OFFICE.

DAVID F. GRAHAM, OF COUDERSPORT, PENNSYLVANIA, ASSIGNOR TO GRAHAM ROLLER BEARING COMPANY, OF COUDERSPORT, PENNSYLVANIA, A CORPORATION.

DESIGN FOR A SOCKET-WRENCH.

59,417.

Specification for Design.

Patented Oct. 18, 1921.

Application filed March 22, 1920. Serial No. 367,880. Term of patent 3½ years.

To all whom it may concern:

Be it known that I, DAVID F. GRAHAM, a citizen of the United States, and resident of Coudersport, county of Potter, State of Pennsylvania, (whose post-office address is ½ Graham Roller Bearing Company, Coudersport, Pennsylvania,) have invented a new, original, and ornamental Design for a Socket-Wrench, of which the following is a specification, reference being had to the accom-

panying drawing, forming a part thereof, which is a front perspective of a socket-wrench showing my new design.

I claim:

The ornamental design for a socket wrench as shown.
